UNITED STATES PATENT OFFICE.

MAURICE HIPPOLYTE LOUIS SIZAIRE, OF PARK ROYAL, LONDON, ENGLAND.

DESIGN FOR A RADIATOR FOR AUTOMOBILE-VEHICLES.

55,491.

Specification for Design. Patented June 15, 1920.

Application filed April 13, 1920. Serial No. 373,560. Term of patent 14 years.

To all whom it may concern:

Be it known that I, MAURICE HIPPOLYTE LOUIS SIZAIRE, a citizen of the French Republic, residing at Park Royal, London, N. W. 10, England, in the county of London, have invented a new, original, and ornamental Design for an Automobile-Radiator, of which the following is a speci-

fication, reference being had to the accompanying drawing, forming part thereof.

Figure 1 is a plan, and

Fig. 2 is a perspective view.

I claim:—

The ornamental design for an automobile radiator as shown.

MAURICE HIPPOLYTE LOUIS SIZAIRE.
